UNITED STATES PATENT OFFICE.

EDWARD C. GRASSMANN, OF MAPLEWOOD, NEW JERSEY, ASSIGNOR TO HARRY C. SCHICK, INC., A CORPORATION OF NEW JERSEY.

CLASP FOR NECKLACES, CHAINS, LAVALIERS, ETC.

Application filed May 26, 1928. Serial No. 280,763.

The present invention relates, generally, to a snap clasp for articles of jewelry; and the invention relates, more particularly, to a snap clasp for strings of beads and so on, which clasp is of one piece of metal and is adapted for receiving a decorative design or configuration.

It is an object of this invention to provide a snap clasp which is made of a single piece 10 of metal, has a part formed to receive a decorative design, and a part adapted to tend to hold the parts of the clasp in the closed position with respect to each other.

Other objects and advantages of the invention will appear from reading the following 15 description of an illustrative embodiment of the invention and from a study of the drawing showing the same; and the invention also consists in the combinations and arrangements of parts set forth in the appended 20 claim.

In the drawing, which illustrates one form of the invention and a modification thereof;

Figure 1 is a top plan view of a snap clasp 25 connecting a string of beads, the latter shown in part;

Figure 2 is a side elevation view of the parts shown in Figure 1;

Figure 3 is a bottom plan view of the same 30 with one end of the string of beads unclasped; and

Figures 4 and 5 are, respectively, a side elevation view in part section and a bottom plan view of a modified form of the clasp of 35 the invention.

In all the above described figures of the drawing like characters of reference are used throughout to indicate corresponding parts.

Referring now to Figures 1 to 3 of the 40 drawing the reference character 1 indicates a flat body of metal which is oval in plan and has one end 2 which turns under the body 1 and then widens out to form the generally oval under-body 3 which lies parallel to said body 1. At its free end said under-body 3 45 has an offset portion 4 adapted to receive the corresponding end 5 of said body 1, which end 5 is curved downward and then around under said offset portion 4 with its end edge 50 6 turned toward said offset portion 4 and into seating relation with the same. Said end 5 has its outer limit within the plane of said under-body 3 to provide that the clasp is thin and occupies a minimum of space 55 in that direction. The oval shape of body

1 and under-body 3 provides that the structure has sufficient strength for its purpose and that the ends 2 and 5 are small enough for receiving connecting means such as the rings 7 and 8 on the string of beads 9. The oval shape of said body 1 (and also of under-body 3 if desired) further provides a surface for receiving a decorative design 10 either in applique, enamel, engraving or other form to conform with the decorative plan of the whole jewelry article. It is to be understood that the body 1 is not limited to the oval form shown but can be diamond shaped or otherwise varied without departing from the objects and purposes of the invention to 70 provide a clasp which is thin from front to back, which is wide and consequently adapted to carry a decorative design and to lie always with flat surface in line with the string or chain which it secures, and which has a 75 clasp structure for holding it in the closed relation.

In Figures 4 and 5 of the drawing a modified form of the clasp of the invention is shown, which form, in addition to the parts above described for Figs. 1 to 3, has a closing spring 11 preferably formed integral with the rest of clasp by punching a tongue 11, from said under-body 3 and bending it so that in the closed position of the clasp said spring 11 will bear against the inner face of said body 1 and tend to hold said offset portion 4 in seated relation on said inturned edge 6 of said end 5. This further contributes to the function of said ends 2 and 5 to tend to keep 90 said clasp closed.

While I have shown and described and have pointed out in the annexed claim certain novel features of the invention, it will be understood that various omissions, substitutions and changes in the forms and details of the device illustrated and in its use and operation may be made by those skilled in the art without departing from the spirit of the invention.

Having thus described my invention, what I claim and desire to secure by Letters Patent is:

A jewelry clasp comprising, a substantially flat oval shaped under-body having an inwardly offset portion at one end, a flat oval shaped main body having reduced end portions bent over in spaced relation to said main body, one of said end portions being formed integral with an end of said under body and 110

acting to urge the offset portion of said under-body outwardly against the other reduced end portion of said main body, said latter reduced end portion forming a stop for said underbody and lying within the outer plane of said under body so as to serve substantially as a continuation thereof and a tongue shaped spring struck inwardly from said under-body and pressing against the inner side

of said main body, said spring acting to assist in urging the offset portion of said under-body against said latter reduced end portion of said main body. 10

In testimony, that I claim the invention set forth above I have hereunto set my hand 15 this 22nd day of May, 1928.

EDWARD C. GRASSMANN.
